UNITED STATES PATENT OFFICE.

GEORGE MERLE, JR., OF MASPETH, NEW YORK, ASSIGNOR OF ONE-SIXTH TO GEORGE MERLE, SR., ONE-SIXTH TO WILLIAM C. MERLE, ONE-SIXTH TO HENRY C. MERLE, AND ONE-SIXTH TO JOHN MERLE, ALL OF BROOKLYN, NEW YORK.

MULTICOLOR INCRUSTING ON STONES.

Application filed March 5, 1925. Serial No. 13,062.

To all whom it may concern:

Be it known that I, GEORGE MERLE, Jr., a citizen of the United States, and residing at Maspeth, L. I., in the county of Queens 5 and State of New York, have invented certain new and useful Improvements in Multicolor Incrusting on Stones, of which the following is a specification, such as will enable those skilled in the art to which it 10 appertains to make and use the same.

This invention relates to the incrusting of stones of various kinds and classes, such for example as sapphires, rubies, black onyx and similar precious or semi-precious stones, 15 and the object of the invention consists in incrusting stones of the class specified in metals of different color whereby color effects may be produced on the stones in the reproduction of characters, objects or 20 things; and with this and other objects in view the invention consists in an article of manufacture of the class specified, constructed as hereinafter described and claimed.

25 The invention is fully disclosed in the following specification, of which the accompanying drawing forms a part, in which the separate parts of my improvement are designated by suitable reference characters 30 in each of the views, and in which:—

Fig. 1 is a plan view of a stone with incrustings thereon showing the stone mounted in a ring or other setting; and,

35 Fig. 2 is a section on the line 2—2 of Fig. 1.

In the accompanying drawing I have shown for the purpose of illustrating one use of my invention, a stone 5 such for example as a black onyx which for illustrative purposes is mounted in a ring setting 40 6, and on the outer face of the stone 5 is arranged incrusting to represent a flower, such for example as a daisy the petals 7 of which are reproduced from aluminum in 45 crustings in the stone 5, while the pollen 8 and stem 9 of the flower is reproduced in gold incrustings.

In the foregoing it will be apparent that 50 the daisy will be reproduced on the black stone 5, silvery petals representing white petals of a daisy, and the gold stem and pollen representing a contrasting color which will set off the flower to produce a very pleasing and beautiful effect.

Heretofore it has been a common practice to incrust stones of various kinds and classes to reproduce thereon designs of characters, objects or things but, in the present procedure it has been customary to reproduce such designs all in one color on 55 a single stone, that is to say, all aluminum incrusting would be employed or all gold incrusting, and the object of my invention consists in arranging on a single stone, 60 metals of two or more contrasting colors 65 to bring out more pleasing and natural effects in the incrusting work to be applied to the stone.

The incrusting may be done in accordance with either the acid or the engraving 70 process, and in the latter method of procedure the stone is first engraved by a suitable tool to cut in the surface of the stone the desired design or artistic reproduction, which may be a character, object or thing, 75 after which twenty-four karat solid gold rolled very thin and aluminum also rolled very thin is pressed in the engravings where the different metals are required to bring out the desired artistic production, after 80 which the projections of the gold and aluminum that extend above the top face of the stone may be filed down flush with the stone surface and, if desired, the metal pressed into the engravings may be configurated or 85 cut to bring out other artistic effects.

In the other method of procedure which is preferably used in connection with the softer stone, the stone is first placed in a cover or jacket of tin foil which snugly fits 90 the periphery of the stone and entirely encloses it, after which a stencil is placed upon the top face of the stone and the tin foil around the stencil is cut by a suitable tool to remove portions of the tin foil in reproducing the stencil thereon, after which a number of the stones thus formed are placed in a tray or bath with the top stenciled faces thereof exposed to a suitable acid and after the stones have remained in the bath 95 a predetermined length of time sufficient to etch or form recesses in the stone corresponding to the stencil on the tin foil and the stones removed from the tray and also from the tin foil the etchings are undercut by a suitable tool and the above procedure of placing the thin gold and thin aluminum 100 in the grooves or recesses of the stone is 105

performed. The undercutting of the walls serves to prevent the accidental displacement of the incrusted metal as will be apparent.

It will be understood that while I have shown the reproduction of a daisy on the face of a black onyx, my invention is not limited in this respect as emblems, shields, other floral designs and the like may be reproduced on any kind or class of stones or stones of any shape on which incrusting work can be done. It will also be understood that flowers or other objects may be merely outlined on the stone and the color of the stone itself used as a background or color for the flower or object to be reproduced, as for example in reproducing a red rose on a ruby, the outline of the rose only need be incrusted in one metal, such for example as aluminum, and the stem and other portions of the flower may be reproduced in the gold, and while I have shown and described certain details of construction for carrying my invention into effect, it will be understood that I am not necessarily limited in these respects and various changes in and modifications of the construction

herein shown and described may be made, within the scope of the appended claims, without departing from the spirit of my invention or sacrificing its advantages.

Having fully described my invention, what I claim as new and desire to secure by Letters Patent, is:—

1. An article of manufacture comprising a stone, on which is incrusted sheet aluminum of such structure as to retain lustre when subjected to the elements, and sheet gold of a color contrasting to that of the aluminum in predetermined arrangement in the production of a predetermined design on said stone.

2. A stone in which is incrusted a combination of precious and non-precious metals of contrasting colors, the non-precious metal being of a white or silvery color and of such structure as to retain its lustre when subjected to the elements.

In testimony that I claim the foregoing as my invention I have signed my name this 28th day of Feb. 1925.

GEORGE MERLE, Jr.
